UNITED STATES PATENT OFFICE.

DORSEY FROST ASBURY, OF WASHINGTON, DISTRICT OF COLUMBIA, ASSIGNOR
TO UNITED STATES ORDNANCE COMPANY, OF WASHINGTON, DISTRICT OF
COLUMBIA, A CORPORATION OF VIRGINIA.

BREECH MECHANISM.

1,186,266.

Specification of Letters Patent. Patented June 6, 1916.

Application filed July 21, 1915. Serial No. 41,063.

To all whom it may concern:

Be it known that I, DORSEY F. ASBURY, a citizen of the United States, and resident of the city of Washington, in the District of Columbia, have invented certain new and useful Improvements in Breech Mechanisms, of which the following is a specification.

My invention relates to breech mechanisms and particularly that type of breech mechanism wherein a cam device is employed for the purpose of translating the swinging movement of the breech plug into rotary movement.

In breech mechanisms of the type referred to a very strong mushroom spring is employed in an effort to prevent the mushroom flying forward in the operation of closing the breech. This spring reacts against the gas check pad so that relatively great power is required to rotate the plug against the gas check pad's surface. These mushroom springs heretofore have not been entirely successful in holding the mushroom against flying forward with the result that considerable of the energy stored in the mushroom necessary for the most effective operation of the cam device in translating motion is lost, while on the other hand the rebound of the mushroom under the influence of the relatively strong spring will cause chattering of the bushing threads and the plug threads.

It is therefore the object of my invention to reduce the unit pressure between the rear surface of the pad and the forward surface of the plug; to keep the mushroom from flying forward when the plug's swing home is arrested; to hold the pad in place by a very weak spring; to hold the pad against the forward face of the plug by means reacting against the plug; to provide a structure by which the tension of the mushroom spring is not affected by the rotation of the plug; to avoid any pressure between the carrier spindle and plug threads and between the plug and breech bushing interrupted threads; to provide means whereby all the swinging energy of the mushroom can be held and transmitted to plug rotation energy through the plug rotating cam; and to provide means for attaining the above objects that can be easily fitted on breech mechanisms now in use.

In the drawings chosen for the purpose of

illustrating my invention, the scope whereof is pointed out in the claim, Figure 1 is a horizontal section through a portion of the breech mechanism embodying the invention, those parts of the mechanism not essential to an understanding of the invention being omitted for the sake of clearness, and Fig. 2, a section on the line 2-2 of Fig. 1.

Referring to the drawing A indicates the gun A' the plug bushing A² the interrupted threads of the plug bushing.

B indicates the plug and B' the interrupted threads of the plug, which co-operates with the threads A² in the usual and well known manner. The swinging carrier of the gun is indicated at C and includes the usual tubular spindle C' upon which the plug B is rotatably engaged by means of threads C². The mushroom of the gun is indicated at D and includes a stem D' slidably engaged in the plug B and the bore of the spindle C'. This stem D' carries the usual nut D², that portion of the bore of the spindle in which the nut D² is disposed being enlarged to form a shoulder 10. The swinging movement of the plug B in the closing of the breech is translated into a rotary movement by a cam device E which may be of any desired construction, the only essential being that a cam device be employed for translating the swinging movement of the plug into rotary movement as the plug moves into the breech in order that the effectiveness of such cam device may be enhanced through the medium of the related structure of the breech mechanism embodied in my invention.

Interposed between the mushroom D and the front face of the plug B is a gas check pad 11 embodying the usual rings 12. Disposed in the major portion of the bore of the spindle C' is a cup 13 situated between the shoulder 10 and the nut D², the open end of said cup being disposed adjacent the nut D². Slidably mounted in the carrier spindle C' is a plurality of compression rods 14, preferably three in number, which bear at one end against the closed end of the cup 13 and their other end against a ring 15 which directly abuts the plug B. It will be noted that I only employ the ring 15 for the purpose of getting a hardened surface for the rods 14 to act against and for the purposes of this invention such ring will be

considered as a part of the breech plug. Encircling the mushroom stem D' is a relatively weak spring 16 which is disposed within the cup 13 and bears at one end against the closed end of the cup and at its other end against the nut D². This spring 16 acts upon the mushroom D to compress the pad 11 between same and the forward end of the plug B. By providing the cup 10 13 and interposing same between the shoulder 10 and the nut D² I limit the forward movement of the mushroom to approximately three hundredths of an inch, such limitation of movement being effected by 15 engagement of the nut D² with the cup 13 as will be obvious.

The action of the cam device forming an element of this invention takes place before the plug is home and the pad seated and 20 under such conditions if the mushroom were to fly forward and the gas check rings get out of their position in respect with the pad and the seat in the gun the energy stored in the mushroom would be lost with respect 25 to its utilization by the cam device in effecting translation of motion. In addition the proper functioning of the gas check pad would be interfered with. By providing a positive stop in the form of the cup 13 acting 30 through the compression rods 14 against the plug B to limit the forward movement of the mushroom I am enabled to conserve all the swinging energy of the mushroom for utilization by the cam device in translating 35 the swinging motion of the plug to rotary motion and at the same time I obviate the possibility of the gas check rings getting out of their position. As the spring 16 no longer serves the purpose of holding 40 the mushroom against forward movement it will be apparent that my structure only necessitates the use of a relatively weak spring sufficient to hold the gas check pad and ring taut.

45 By arranging the mechanism so that the spring compressing means reacts against the plug it will be obvious that rotation of the

plug will not tighten or loosen the tension of the spring even though the threads on the plug carrier spindle have a lead. By 50 compressing the mushroom spring against the plug and not against the carrier the threads on the carrier spindle are allowed to float during the plug's rotation and do not offer any resistance due to the mushroom 55 spring as heretofore and as these threads float the interrupted threads on the plug and breech bushing naturally assume their easiest rotating position, in other words the plug and breech bushing threads also float. 60 This floating condition obviates a relatively large amount of friction and therefore less power is needed to rotate the plug through the medium of the cam device.

By providing the cup 13 and relatively 65 small spring 16 I am enabled to fit same in the space heretofore used in mounting the large strong spring. The holes in the carrier for the compression rods 14 are drilled with a jig which has only one hole, the jig 70 is turned for the drilling of the other holes. The compression rod holes in the carrier do not weaken the spindle as they pass through an extra strong section.

What I claim and desire to secure by Letters Patent is:—

In a gun, the combination of a swinging carrier, a rotatable breech plug, a mushroom, a cam device for translating the motion of the plug as the latter enters the 80 breech, and non-elastic means for holding the mushroom against forward movement relatively to the plug during rotary movement of the latter whereby all the swinging energy of the mushroom will be conserved 85 and translated to plug rotation energy through the cam device.

In testimony whereof, I affix my signature, in the presence of two witnesses.

DORSEY FROST ASBURY.
